CIRCUIT BREAKER

Fritz Kesselring, Berlin-Hermsdorf, Germany, assignor to Westinghouse Electric & Manufacturing Company, East Pittsburgh, Pa., a corporation of Pennsylvania

Application May 4, 1934, Serial No. 723,891
In Germany October 20, 1933

3 Claims. (Cl. 200—148)

My invention relates to circuit breakers of the type wherein a flowing stream or jet of gas or vapor is used for extinguishing the arc which is established incident to the opening of the controlled circuit. Ordinarily, such breakers comprise a gas reservoir, an arc chamber and means for causing a flow of gas from the reservoir through the arc. The gas is usually discharged to the atmosphere, thus limiting the availability of gaseous substances for use with these breakers to those substances which are relatively inexpensive. The gas which is almost invariably used is air, and while reasonably satisfactory results have been secured with air-jet breakers, their operation is not as satisfactory as might be desired.

One reason advanced for the unsatisfactory operation of these breakers has been the unsuitability of air—compared with certain other gaseous or vapor substances—as an arc extinguishing medium, and an extended investigation of the operational characteristics of this type circuit breaker indicates that this reason is the correct one. It appears from this investigation that two types of gases are particularly suitable for use in extinguishing electrical arcs. One type includes those gases which have good heat conductivity and high diffusion capacity. This group includes hydrogen, helium, and mercury vapor. The other type includes those inert and not readily ionizable gases such as argon, neon, crypton and xenon.

All of these gases, however, are relatively expensive, and if a circuit breaker wherein they are to be used is to be commercially practicable, some means must be provided whereby the gas or vapor can be used repeatedly for accomplishing arc extinction.

This is the principal object of my invention, and the particular method which I prefer to utilize in accomplishing this object consists in the provision of a circuit breaker wherein the arc is established within a closed pressure system which includes means for causing a blast of gas or vapor therethrough.

More specifically, the circuit breaker of my invention includes a high pressure storage tank for the arc extinguishing gas, a low pressure tank, conducting means which includes an arc passage intermediate the two tanks, means for drawing the arc within the arc passage, means for causing a flow of gas from the high pressure tank through the arc passage to the low pressure tank during the circuit opening operation, and a compressor or similar means for returning the gas to

the high pressure tank following each circuit opening operation. By virtue of this arrangement the gas may be used repeatedly, and it is necessary that only a small quantity be provided for each individual breaker. The cost of the breaker is thus reduced to a minimum.

It is, of course, necessary that the chemical and physical properties of a gas or vapor suitable for use with a circuit breaker of this type shall not be permanently affected by being brought in contact with an electric arc. All of the elemental gases mentioned above meet this requirement either when used alone or in mixtures with each other.

It is of particular importance that all parts of the closed pressure system of the breaker shall be entirely gas-tight in order to prevent atmospheric dilution, and a particularly effective means of preventing dilution consists in the maintaining of the pressure within the system at a value higher than the atmospheric pressure. If this is done, any small leakage will not affect the arc interrupting ability of the breaker. In order to indicate leaks in the pressure system, an odorant may be added to the gas or vapor, and, if desired, a refilling device may be associated with the pressure system for automatically replacing any gas which might be lost.

Referring to the drawing:

Figure 1 is an elevational view, partially in section, of a single-pole circuit breaker embodying the principal elements of my invention.

Fig. 2 is a front elevational view of the circuit breaker illustrated in Fig. 1.

Fig. 3 is a sectional view of a modified form of the circuit interrupter illustrated in Fig. 1.

Fig. 4 is an elevational view of the circuit interrupter shown in Fig. 3, and

Fig. 5 is a schematic view of one form of control circuit for the breaker shown in Figs. 1 and 2.

As shown in Figs. 1 and 2, the preferred form of my invention comprises a base 1 upon which are mounted a pair of hollow supporting insulators 3 and 5. The upper insulator 3 is adapted to support a high pressure tank 7, and the lower insulator 5 is in turn adapted to support a low pressure tank 9. An insulating conduit 11 extends from the high pressure tank 7 through the hollow upper insulator 3, the base 1 and the lower hollow insulator 5 to the low pressure tank 9, and is used for returning the gas to the high pressure tank following the arc extinguishing operation.

An electro-magnetically operated valve 13 is positioned in the metallic conduit 15 leading from the high pressure tank 7 toward the low pres-

sure tank 8. This conduit 15 terminates in a tubular-shaped fixed contact 17 which is adapted to cooperate with a suitable rod-shaped movable contact 19.

- 5 The movable contact 18 is supported upon a piston member 21 which is adapted to move within a cylinder 23 rigidly affixed to the low pressure tank 8. The piston 21 is of magnetic material and is adapted to be moved upwardly within the cylinder 23 by means of a coil 25. The piston 21 is moved to the open circuit position under the combined influence of gravity and the gas pressure existing within the closed pressure system during the circuit opening operation.

10 15 A tubular insulating member 27 extends between the cylinder 23 and the conduit 15 extending downwardly from the high pressure tank 7 and serves to define the passage 29 wherein the arc is drawn and extinguished. The joints between the insulating member 27, the conduit 15, and the cylinder member 23 are all made gas-tight, as are the joints between the two tanks and the conduit 11 in order that an entirely enclosed pressure system shall be provided.

20 25 The lower portion of the cylinder member 23 is provided with a pair of opposed lateral openings 31 which open into the low pressure tank 8. When the breaker is in the closed circuit position, the piston 21 moves so as to close the arc passage 29 from the low pressure tank. When the piston 21 moves to the open circuit position, however, these lateral openings 31 are uncovered, and the arc passage 29 is directly connected with the low pressure cylinder 8 in order that the gas blast initiated by the operation of the electro-magnetic valve 13 shall flow into the low pressure cylinder.

30 35

In order to return the gas which flows into the low pressure cylinder 9 during each arc extinguishing operation, a compressor 33 is provided as shown in the drawing. This compressor is disposed entirely within the low pressure cylinder 9. The motor 35 which actuates this compressor is controlled by a valve 37 which is responsive to the difference in pressure existing between the high pressure and the low pressure tanks; the operation of the compressor is thus entirely automatic. This valve 37 also serves to normally close the conduit 11 leading from the low pressure tank to the high pressure tank, and since the electromagnetic valve 13 is also normally closed, there is little possibility of leakage from the high pressure tank to the low pressure tank when the breaker is standing idle for long periods in either the open or the closed circuit position.

53 Ordinarily the pressure within all parts of the system is maintained somewhat above atmospheric in order that the gas within the closed pressure system shall not be diluted with air. If desired, a means such as the cylinder 38 of compressed gas may be provided for replacing any leakage which might occur over long periods of time.

As mentioned above, when the breaker is in the closed circuit position, the arcing chamber 28 is sealed from the low pressure tank by means of the piston 24. Thus when the electromagnetic valve 18 operates during the circuit opening operation to connect the high pressure tank 7 with the arcing chamber, the full force of this pressure is made available for accelerating movement of the movable contact member 19 toward the open circuit portion. This is of considerable value in facilitating the interrupting of high voltage circuits.

The electrical circuit for the breaker is comparatively direct. Beginning with the upper ter-

One form of control circuit for the breaker is shown schematically in Fig. 5. The circuit includes a three position switch 47, an overload relay 48, and suitable conducting means for completing the electrical circuit to the various parts. The control circuit is so arranged that the breaker may be opened or closed through the actuation of the three position switch 47, provided that an overload capable of actuating the relay 49 does not exist in the power circuit. If such an overload does exist the breaker will automatically open regardless of the position of the switch 47. During the opening operation, the closing coil 25 is always deenergized and the electromagnetically operated valve 13 is always energized.

The circuit interrupter is shown in the closed circuit position in Fig. 1. In the device illustrated, it is intended that the cooperating portions of the contacts 17 and 18 shall be held in engagement with each other by the magnetic effect of the closing coil 25. In this position, the movable blade 58 of the three position switch 47 engages the contact jaw 51 thereby completing the electrical circuit from one terminal of the control circuit to the contact point 53 of the relay 49. The circuit through the relay is completed by the movable conducting means 55 which bridges the contact points 53 and 51, and the point 57 is connected to one side of the closing coil 25. The other side of the coil 25 is directly connected to the other side of the control circuit.

To open the breaker manually, the switch 41 is moved to complete the circuit to the second contact jaw 59. This movement causes the energization of the electromagnetically operated valve 13, and simultaneously deenergizes the closing coil 25. The moving contact 18 is then subjected to the combined forces of gravity and the pressure of the gas flowing through the hollow contact 17 from the high pressure tank 7, and, as a result, moves to the open circuit position with very high velocity. A stream of gas flows through the hollow contact 17 and the arc passage 28 and effects a rapid extinguishment 50 of the arc formed therein.

Immediately following the arc extinguishing operation the electromagnetic valve 13 automatically closes the conduit 15 leading from the high pressure tank 7 to the arcing chamber 29. This prevents waste of the gas and prolonged operation of the compressor. If the interrupter is to remain in the open circuit position for any prolonged period the blade member 50 is moved into engagement with the central jaw 63, thereby de-energizing all of the breaker actuating means except the actuating relay 37 for the compressor motor 35. In order that a sufficient pressure shall at all times be maintained within the high pressure tank, the relay 37 is never disconnected from the control power circuit.

When the interrupter is in the closed circuit position and an overload of sufficient magnitude to actuate the overload relay 48 occurs, the armature 66 of that relay lifts the bridging mem- 75

ber 55 (against the biasing spring 66) and causes that member to move so as to open the circuit between the contact points 53 and 57 to simultaneously complete the circuit between the contact points 67 and 69. This movement effects a simultaneous energization of the electromagnetic valve 13 and a deenergization of the closing coil 25 whereupon the breaker opens exactly as described above for manual operation. Following the opening of the circuit, the armature 65 may be latched in an intermediate position, in order that the circuit through the contact points 53 and 57 and the circuit through points 67 and 69 shall be open. This will prevent the breaker from automatically reclosing if the switch 47 is not moved to the mid or normal open circuit position. If desired, a mechanical interlock may be provided for automatically moving the switch 47 to the neutral position when the breaker opens.

To close the circuit through the interrupter following an opening operation (either automatic or in response to movement of the switch 47), the switch blade 50 is moved to the closed position. The closing coil 25 is thereby energized and the magnetic piston 21 moves the contact rod into engagement with the fixed contact. Immediately following the arc extinction operation, the electro-magnetic valve 13 automatically closes the conduit 15 leading from the high pressure tank 7 to the arcing chamber 29, and since the piston 21 substantially seals the cylinder 23 wherein it moves, the upward movement of the contact during the circuit closing operation is cushioned by virtue of the gas which is entrapped within the arc passage 29. This prevents damage to the engaging contact surfaces.

When the circuit interrupter is carrying a small load and the circuit opening operation is initiated, it often happens that the arc established incident to the separation of the contacts is extinguished before the lateral openings 31 to the low pressure cylinder 9 are uncovered by the downwardly moving piston 21. If this happens, the electromagnetic valve 13 immediately closes the conduit 15 between the high pressure tank 7 and the arcing chamber 29 and thereby reduces to a minimum the amount of high pressure gas which is used during the opening of the circuit. This arrangement limits the power used by the compressor 33 and is of great value in securing reliable operation of the device.

The modification illustrated in Figs. 3 and 4 is essentially similar to the device shown in Figs. 1 and 2. It includes a low pressure tank 71, a high pressure tank 73, a conduit 75 leading from the high pressure tank to the low pressure tank, a compressor 77 adapted to cooperate with the conduit 75 to return the gas which flows into the low pressure cylinder during the arc extinguishing operation to the high pressure cylinder, a pair of hollow insulators 79 and 81, an arcing chamber 83 the walls of which are of insulating material, and suitable conduit means intermediate the arcing chamber and the hollow insulator. The hollow insulators themselves form a part of the closed pressure system in this embodiment.

It will be noted that the high pressure cylinder 73 is positioned entirely within the low pressure cylinder 71, and that the compressor 77 and the actuating motor 85 therefor are mounted within a suitable air-dome 87 supported upon the low pressure tank 71. This arrangement is of considerable value in facilitating the servicing of the apparatus and in preventing the loss of any gas which might lead from the high pressure tank.

The electromagnetically operated valve 89, which corresponds to the valve 13 shown in the structure of Fig. 1, and the associated conduit means 91 are disposed intermediate the left-hand hollow insulator 81 and the high pressure tank 73. A metallic conduit means 93 is disposed intermediate the left-hand hollow insulator 81 and the arc passage 83 and is provided with a cylinder portion 95 wherein the piston member 97 of magnetic material is adapted to move. The left hand terminal 99 is affixed to this magnetic conduit means.

The other metallic conduit means 101 which is disposed intermediate the right-hand hollow insulator 79 and the arcing chamber 83 is provided with a tubular stationary contact 103 similar to the contact 11 of the breaker shown in Figs. 1 and 2. In addition, this conduit 101 is provided with a plurality of suitably proportioned fins 105 for radiating heat therefrom. A plurality of metallic cooling members 107 are disposed within the conduit 101 and the body portion of the insulator 79. The fins 105 and the metallic cooling members 107 are positioned immediately subsequent, with respect to the path of flow of the arc extinguishing gas, to the arc passage and are of service in preventing undue heating of the gas which flows into the low pressure tank 71, during the operation of the interrupter, and thus assure that the back pressure existing therein will not be excessively large.

The moving contact 109 is similar in design to the moving contact 19 of the device shown in Figs. 1 and 2. Two operating coils 111 and 113 are provided for moving the piston 97 to open and to close the circuit.

The other terminal 115 of the interrupter is affixed to the metallic conduit 101 thus producing a very simple and very direct current path through the interrupter. The shunt 117 serves to electrically connect the plunger with the movable contact and piston assemblage.

The control circuit for the interrupter shown in Figs. 3 and 4 may be exactly similar to the circuit shown in Fig. 5, it being necessary merely to parallel the opening coil 113 with the electro-magnetic valve.

The operation of the breaker illustrated in Figs. 3 and 4 is essentially similar to the operation of the breaker illustrated in Figs. 1 and 2. Upon the occurrence of an overload or other abnormal condition capable of actuating the control relay, or upon the manual operation of the control switch, the electro-magnetically operated valve 89 opens and causes a quantity of the gas entrapped within the high pressure cylinder 73 to flow through the conduit 91 and the insulator 81 into the conduit 93 and the arc passage 83. The pressure of the gas aided by the energization of the opening coil 113 moves the plunger 97 and with it the moving contact 109 so as to establish an arc within the arc passage. The gas flows through the arc passage and the hollow stationary contact 103 into the conduit 101 and thence through the other hollow insulator 79 into the low pressure cylinder 71. The out-flowing heated gas, as mentioned before, is cooled by means of the metallic cooling members 107 disposed within the closed pressure system and the cooling fins 105.

The entire pressure system is, of course, gas-tight and the operation of the motor 85 driving the compressor 77 is controlled by means of a valve 119 responsive to the difference of pressure 75

between the high pressure and the low pressure tanks.

It will thus be seen that I have disclosed a new improved circuit interrupter which utilizes a blast 5 of a gas that is particularly effective in accomplishing the extinction of an electric arc and which is provided with a closed pressure system whereby the gas may be used repeatedly during the life of the interrupter. This feature, whereby 10 the same quantity of gas may be used a number of times is the principal feature of my invention. I have disclosed, however, certain preferred structural arrangements which are of particular value in carrying out the objects of my invention, and 15 I have also disclosed certain preferred gases and vapors which I have found particularly suitable for effecting arc extinguishment in a circuit interrupter of the gas blast type.

The two preferred forms of my invention which 20 have been described in the foregoing specification are both of the single breaker, single pole type. It is, of course, within the province of my invention that a multi-break circuit interrupter, or a multi-pole circuit interrupter, utilizing a single 25 high pressure tank and a single low pressure tank could be used. Numerous other arrangements likewise within the province of my invention will be apparent to one skilled in the art.

While in accordance with the patent statutes 30 I have disclosed the foregoing details of certain preferred forms of my invention, it is to be understood that the principles disclosed are capable of wide adaptation to the art of circuit interruption generally. It is my desire therefore 35 that the language of the accompanying claims should be accorded the broadest reasonable construction and that my invention shall be limited only by what is expressly stated therein and by the prior art.

40 I claim as my invention:

1. In a circuit interrupter; means for drawing an arc; a volume of arc extinguishing gas; means for causing a quantity of said gas to flow through said arc to effect its extinguishment; and means 45 comprising a closed pressure system for permitting said quantity of gas to be used repeatedly without substantial loss; said closed pressure system including a high pressure tank wherein said

gas is normally contained under considerable pressure, a low pressure tank into which said gas flows during each arc extinguishing operation, means for preventing said gas from flowing from said high pressure tank except during each opening operation of said interrupter, and a compressor for returning the gas which flows into the low pressure tank during the operation of the interrupter to the high pressure tank; said compressor being disposed entirely within one of said 10 tanks.

2. In a circuit interrupter; means for drawing an arc; a volume of arc extinguishing gas; means for causing a quantity of said gas to flow through said arc during each operation of said interrupter 15 to effect its extinguishment; and means comprising a closed pressure system for permitting said volume of gas to be used repeatedly without substantial loss; said closed pressure system including a high pressure tank wherein said gas is normally contained under high pressure, a low pressure tank into which said gas flows during each arc extinguishing operation, and a compressor for returning the gas which flows into the low pressure tank during the operation of the interrupter to the high pressure tank; said high pressure tank being disposed entirely within said low pressure tank, and being provided with valve means for preventing said gas from flowing to said low pressure tank except during the arc extinguishing operation. 20 25

3. In a circuit interrupter; means defining a closed pressure system one portion of which comprises an arc passage; means for drawing an arc within said arc passage; means for introducing a quantity of a gas, into the arc passage portion of said closed system under sufficient pressure to cause a flow of gas through the arc; and means whereby said quantity of gas is used repeatedly, without substantial loss, during the operation of 40 said interrupter; said closed pressure system including a metallic conduit portion positioned, with respect to the normal direction of flow of said gas, subsequent to the arc passage; said metallic conduit portion being provided with externally disposed metallic cooling fins and internally disposed metallic cooling members. 35 45

FRITZ KESSELRING.
